US00D630505S

(12) **United States Design Patent**
Westemeyer et al.

(10) **Patent No.:** **US D630,505 S**
(45) **Date of Patent:** **** Jan. 11, 2011**

(54) **ABSORBENT ARTICLE CONTAINER**

(75) Inventors: **Jennifer Lea Westemeyer**, Neenah, WI (US); **George Ikuya Nukuto**, Neenah, WI (US); **Jane Louise Clough**, Neenah, WI (US); **Dean Martin Wydeven**, Appleton, WI (US)

(73) Assignee: **Kimberly-Clark Worldwide, Inc.**, Neenah, WI (US)

(**) Term: **14 Years**

(21) Appl. No.: **29/358,449**

(22) Filed: **Mar. 26, 2010**

(51) **LOC (9) Cl.** **09-03**

(52) **U.S. Cl.** **D9/426; D9/734**

(58) **Field of Classification Search** D3/201, D3/273, 274, 276, 275, 292, 294, 295, 298, D3/901; D6/515, 518; D7/629; D9/414, D9/415, 420, 421, 422, 423, 424, 425, 426, D9/430, 730, 734; D28/76, 77, 78, 81, 83; 132/293, 294, 295, 296, 297, 298, 299, 300, 132/301, 302, 303, 304, 305, 306, 307; 206/235, 206/581, 823; 220/253, 254

See application file for complete search history.

(57) **CLAIM**

We claim the ornamental design for an absorbent article container, as shown and described.

DESCRIPTION

FIG. 1 is a top perspective view of the absorbent article container.

FIG. 2 is a top view of the absorbent article container of FIG. 1.

FIG. 3 is a bottom view of the absorbent article container of FIG. 1.

FIG. 4 is a front side view of the absorbent article container of FIG. 1.

FIG. 5 is a back side view of the absorbent article container of FIG. 1.

FIG. 6 is a right side view of the absorbent article container of FIG. 1; and,

FIG. 7 is a left side view of the absorbent article container of FIG. 1.
